RAILWAY TRAFFIC CONTROLLING
APPARATUSCharles H. Lay, Pittsburgh, Pa., assignor to The
Union Switch & Signal Company, Swissvale,
Pa., a corporation of Pennsylvania

Application April 5, 1935, Serial No. 14,861

11 Claims. (Cl. 246—46)

My invention relates to railway traffic controlling apparatus, and particularly to apparatus for the automatic control of railway signals and/or train stopping devices. One feature of my invention is the provision of novel and improved means for giving more than three restrictive indications in the rear of a train.

I will describe one form of apparatus embodying my invention, and will then point out the novel features thereof in claims.

In the accompanying drawings, Figs. 1^a and 1^b when placed end to end with Fig. 1^a on the left, constitute a diagrammatic view showing one form of apparatus embodying my invention; Fig. 2 is a diagrammatic view showing an alternative apparatus embodying my invention; while Fig. 3 is a view, partly diagrammatic, and partly an isometric projection, illustrating one form of relay suitable for use in the circuit arrangements shown in Figs. 1^a, 1^b and 2.

The structure of the relay shown in Fig. 3 will first be described and the circuits illustrated by Figs. 1^a, 1^b and 2 employing this type of relay will then be described. The relay of Fig. 3 comprises a main electromagnet A of the usual type having two parallel cores 11^a and 11^b connected together at their upper ends by a backstrap 30, and provided at their lower ends with enlarged pole pieces 2^a and 2^b, respectively. The core 11^a carries the usual operating winding 4^a and an auxiliary winding 20^a, and the core 11^b likewise carries the usual operating winding 4^b and an auxiliary winding 20^b, the windings 4^a and 20^a being similar in all respects to the windings 4^b and 20^b, respectively. The windings 4^a and 4^b are connected in series to be cumulative in the usual manner, and are supplied with direct current from a suitable source, such as a battery 50, through a pole-changer 60. The windings 20^a and 20^b are likewise connected in series to be cumulative for a purpose which will be described in detail hereinafter.

Attached to the rear sides of the pole pieces 2^a and 2^b is a non-magnetizable bracket 70 which carries two pivot screws 80, only one of which pivot screws is visible in the drawings, and pivotally mounted on the screws 80 for swinging movement toward or away from the pole pieces 2^a and 2^b is a main tractive armature 90. A contact finger 10^c is secured to, but insulated from, the under side of the armature 90, and is adapted to engage a fixed contact block 10^a or 10^b to close a contact 10^c—10^a or 10^c—10^b in the usual and well-known manner.

Associated with the electromagnet A is a constantly magnetized core 11^c, here shown as a permanent magnet, the upper end of which engages the under side of the backstrap 30, and the lower end of which is provided with a bifurcated pole piece 42. Pivotaly supported between the bifurcations of the pole piece 42 on terminal screws 43 screwed through the bifurcations, is a polarized armature 44 which extends equidistant through the pivot. The pole pieces 2^a and 2^b of the main electromagnet A are provided with integral extensions 15^a and 15^b, respectively, the pole faces of which overlie the opposite ends of the armature 44, and it will be apparent, therefore, that the polarized armature 44 will swing toward one or the other of these extensions, depending upon the polarity of the current which is supplied to the windings 4^a and 4^b. When the polarized armature 44 is swung toward the extension 15^a, as shown, a contact finger 16^c fastened to this armature by means of an insulating support 47 engages a fixed contact block 16^b to close a contact 16^c—16^b. When the polarized armature is swung toward the extension 15^b, however, the contact finger 16^c moves out of engagement with the fixed contact block 16^b and into engagement with a fixed contact block 16^a, thus opening contact 16^c—16^b and closing a contact 16^c—16^a.

It should be noted that while, for purposes of illustration, I have shown the main and polarized armatures each provided with only one contact finger, these armatures may each be provided with as many other contact fingers as is desired.

The reference character B designates an auxiliary electromagnet comprising a pair of parallel cores 18^a and 18^b connected together at their upper ends by a magnetizable backstrap 49, and provided at their lower ends with enlarged pole pieces 21^a and 21^b having integral U-shaped extensions 22^a and 22^b, respectively. Surrounding the cores 18^a and 18^b are windings 23^a and 23^b, which windings, as here shown, are cumulatively connected in series. The windings 23^a and 23^b are also connected in series with the auxiliary windings 20^a and 20^b of the main electromagnet A, and externally controlled contacts Q; and it will be apparent, therefore, that with these contacts closed any change in flux in the cores of the main electromagnet will cause a current to flow in the circuit including the windings 20^a, 20^b, 23^a and 23^b, thus setting up a flux in the auxiliary electromagnet B. Cooperating with the pole pieces 21^a and 21^b, and with the extensions 22^a and 22^b on these pole pieces 55

is an auxiliary armature 34 which is attached to the main armature 90 by means of a non-magnetizable connecting member 45. The parts are so proportioned that when the main armature 90 is picked up, the auxiliary armature 34 will be mechanically held in an upper position in which it engages pole faces 26^a and 26^b formed on the under side of the pole pieces 21^a and 21^b, respectively, but that when the main armature 90 is released, the auxiliary armature 34 will then be moved to a lowermost position in which it rests on pole faces 27^a and 27^b formed on the extensions 22^a and 22^b of the pole pieces 21^a and 21^b, respectively.

15 As shown in the drawings, pole-changer 60 occupies an intermediate position in which the supply of current to the windings 4^a and 4^b of the main electromagnet A is cut off, and this electromagnet is therefore deenergized. The 20 auxiliary electromagnet B is therefore also deenergized, and armature 90 is accordingly released. Front contact 10^c—10^a controlled by armature 90 is therefore open and back contact 10^c—10^b is closed. Furthermore, since armature 25 90 is released, auxiliary armature 34 occupies its lowermost position. Polarized armature 44 is swung toward extension 15^a of pole piece 21^a, this being the normal position of this armature, and polar contact 16^c—16^b is therefore closed, while 30 polar contact 16^c—16^a is open. Armature 44 is in its normal position merely because the last operation of the relay was to that position.

In explaining the operation of the relay as a whole, I will first assume that pole-changer 60 is moved upwardly to what I shall term its "normal" position, thus supplying current of normal polarity to the windings 4^a and 4^b of the main electromagnet A. This current flowing in the windings 4^a and 4^b sets up a flux in the cores 11^a and 11^b, and while this flux is building up, an electromotive force is induced in the windings 20^a and 20^b by transformer action, which electromotive force causes a current to flow in the windings 23^a and 23^b, thus with contacts Q 40 closed setting up a flux in the auxiliary electromagnet B. Since the auxiliary armature 34 occupies its lowermost position under these conditions, the air gaps between this armature and the pole faces 27^a and 27^b on the auxiliary pole pieces 22^a and 22^b is considerably smaller than the air gaps between the auxiliary armature and the pole faces 26^a and 26^b on the pole pieces 21^a and 21^b, and as a result the flux which is set up in the auxiliary electromagnet flows 45 through the auxiliary armature 34 by way of the auxiliary pole pieces, thus exerting a force on the auxiliary armature tending to hold it in its lowermost position. This force is transmitted to the main armature through the relatively long lever arm afforded by the connecting member 45, and the parts are so proportioned that as long as the flux continues to build up in the cores 11^a and 11^b of the main electromagnet A, this force will be strong enough to prevent the 50 main armature 90 from picking up. As soon, however, as the flux in the main electromagnet reaches a steady state, an electromotive force is no longer induced in the auxiliary windings 20^a and 20^b, and the flux in the auxiliary electromagnet then decays. When this happens, the 55 force tending to hold the auxiliary armature 34 in its lowermost position is removed, and the main armature 90 will then pick up due to the pull exerted on this armature by the main electromagnet. It follows, therefore, that the main

armature 90 is considerably slower in picking up than would be the case if the auxiliary electromagnet and auxiliary armature were not provided. The energization of the main electromagnet A under the conditions just described 5 will not affect the polarized armature 44 since this armature already occupies its normal position.

I will next assume that with the parts in the positions in which they are shown in the drawings, the pole-changer 60, instead of being moved upwardly to its normal position as just described, is moved downwardly to what I shall term its "reverse" position, thus supplying current of reverse polarity to the electromagnet A. Under 10 these conditions, the operation of the relay will be similar to that previously described with the single exception that since the main electromagnet A is now supplied with current of reverse polarity, the polar armature 44, instead of remaining in the position shown, will swing to its reverse position, thus opening contact 16^c—16^a and closing contact 16^c—16^b.

If the relay is energized by current flow through it in either direction at a time that contacts Q 25 are open, the windings 23^a and 23^b will be unable to exert any influence on armature 34, accordingly the main armature 90 will pick up immediately on the closure of a circuit through windings 4^a and 4^b, and will immediately drop on 30 a subsequent opening of the circuit. It will be apparent, therefore, that the armature 90 may be made quick or slow to actuate on any energization or deenergization of windings 4^a and 4^b, depending on the open or closed condition of 35 contacts Q.

I will now assume that with pole changer 60 occupying either its normal or its reverse position, so that the main armature 90 is picked up, the pole-changer is reversed to cause the polarized armature of the relay to reverse. During the reversal of the pole-changer, the flux in the cores 11^a and 11^b of the electromagnet A will rapidly drop to zero, and will then build up in the opposite direction, thus inducing an electromotive force in 45 the windings 20^a and 20^b which will cause a flux to be set up in the cores 18^a and 18^b of the electromagnet B in the manner previously described. Since armature 90 is now picked up, auxiliary armature 34 will occupy its upper position, and the 50 air gaps between this armature and the pole faces 26^a and 26^b on the under side of the pole pieces 21^a and 21^b of the auxiliary electromagnet will be considerably smaller than the air gaps between this armature and the pole faces 27^a and 27^b on the auxiliary pole pieces 22^a and 22^b. As a result, the flux which is set up in the cores of the auxiliary electromagnet B will now flow through the armature 34 by way of the main pole pieces 21^a and 21^b, thus exerting a pull on this armature 60 which acts through the connecting member 45 to prevent the main armature 90 from dropping. It follows that armature 90 will remain picked up during the reversal of the polarity of the current supplied to magnet A. 65

Having made clear the operating characteristics of the polarized relays which I employ, the circuits illustrated in Figs. 1^a and 1^b will now be described. The reference character E designates a railway track along which traffic normally 70 moves in the direction indicated by the arrow. The rails of this track are divided by the usual insulated joints 6 to form a series of track sections 1—2, 2—3, etc. Each section is provided 75 with a track circuit, and these track circuits, as

here shown, are of the center-fed type, comprising a battery 1 connected across the rails at an intermediate point in the section, and two track relays T and AT connected across the rails at 5 the entrance and exit ends, respectively.

Each section is provided with two polarized relays A and B preferably of the type illustrated in Fig. 3, an approach lighting relay L, and a battery C.

10 Each two adjoining sections are provided with a line circuit which includes, in series, relay A for the forward section and relay B for the rear section, and current of normal or reverse polarity is supplied to such circuit according as the B relay 15 for the section next in advance of the forward section is closed or open. Referring to sections 3—4 and 4—5, for example, the line circuit for these sections passes from the plus terminal of battery C3, through the front point of contact 13 of relay 3B, front contact 14 of track relay 4AT, winding of approach lighting relay 3L, front contact 15 of relay 4T, winding of relay 4A, front point of contact 16 of track relay 5AT, front point of contact 17 of track relay 5T, winding of relay 5B, front point of contact 18 of track relay 5T, front point of contact 19 of relay 5AT, front point of contact 20 of relay 4T, front point of contact 21 of relay 4AT, and the front point of contact 22 of relay 3B, to the minus terminal of battery C3. Relay 3B being closed, the current which is supplied to this circuit is of normal polarity, relay 3L is energized, relays 4A and 5B are both energized in the normal direction and the polar contacts of the two latter relays are therefore 35 swung to the left. When relay 3B is open, and the line circuit just traced is closed at all other points, current of reverse polarity is supplied thereto, because of the fact that contacts 13 and 22 of relay 3B function as a pole-changer. Relays 4A and 5B will then be energized in the reverse direction, so that their polar contacts will be swung to the right.

Each section is provided with a signal S comprising two groups of lamps. The upper group 45 is made up of a green lamp GA, a yellow lamp YA, and a red lamp RA. The lower group is similarly made up of a green lamp GB, a yellow lamp YB, and a red lamp RB. Referring particularly to signal S3, when relays 3A and 3B are 50 both energized in the reverse direction, as shown in the drawings, and when approach lighting relay 3L is deenergized, the yellow lamp YA of the upper group will be lighted, the circuit being from the plus terminal of a battery C3, through back 55 contact 8 of relay 3L, front point of contact 11 of relay 3A, polar contact 12 of relay 3A in the reverse position, and lamp YA of signal S3 to the minus terminal of battery C3. The yellow lamp YB of the lower group in this signal will also be 60 lighted, the circuit being from the plus terminal of battery C3, through back contact 8 of relay 3L, front point of contact 9 of relay 3B, polar contact 10 of relay 3B in the reverse position, and lamp YB to the minus terminal of battery C3.

65 When relay 3A becomes energized in the normal direction, lamp GA of signal S3 will become lighted by virtue of a circuit which will be obvious from the drawings. Similarly, when relay 3B becomes energized in the normal direction, lamp 70 GB will become lighted by virtue of a circuit which will be obvious from the drawings. In response to deenergization of relay 3A, red lamp RA will become lighted, the circuit being from the plus terminal of battery C3, through back contact 8 of relay 3L, back point of contact 11 of relay 3A,

and lamp RA to the minus terminal of battery C3. Similarly, when relay 3B opens, red lamp RB will become lighted by virtue of a circuit which will be obvious without detailed explanation. It is understood, of course, that all lamps of signal 5 S3 will be extinguished except when the approach lighting relay 3L is deenergized. The controlling circuits for each of the signals are similar to those which have been traced for signal S3.

As shown in the drawings, an automatic train 10 stopping device D is provided for each track section, and this device is provided with a clearing circuit which is closed when and only when both of the polarized relays A and B for the associated section are energized in the normal direction. 15 Considering the device D3 for section 2—3, for example, the clearing circuit for this device is from one terminal of its operating winding, through polar contact 113 of relay 3B in the normal position, front contact 26 of the same 20 relay, front neutral contact 27 of relay 3A, and polar contact 114 of relay 3A in the normal position, to the other terminal of the operating winding for the device D3.

As shown in the drawings, the section to the 25 left of point 1 is occupied by a train F, so that track relay 1T is open. The circuits for relays 1A and 1B are therefore open, so that these relays are deenergized. If approach lighting relay 1L were deenergized, due to the presence of a 30 train in section 1—2, the red lamps RA and RB of signal S1 would both be lighted. Relay 1B being open, relays 2A and 3B are energized in the reverse direction. Relay 2B is deenergized because its circuit is open at track relay 1T. Relay 2B being open, relays 3A and 4B are energized in the reverse direction. Relay 3B being closed, relays 4A and 5B are energized in normal 35 direction. Relay 5A is energized in the normal direction because relay 4B is closed. 40

At point 2, then, relay 2A is energized in the reverse direction, so that lamp YA of signal S2 is lighted; and relay 2B is deenergized, so that the lamp RB of signal S2 is lighted. (It is assumed at this point, and at all similar points 45 hereinafter, that the approach lighting relay for each signal is deenergized due to the train approaching such signal). This signal then indicates that the second section in advance is occupied. At point 3, both relays 3A and 3B are energized in the reverse direction, so that the yellow lamps YA and YB of signal S3 are both lighted. Signal S3 indicates, therefore, that the third section in advance is occupied by a train. Relay 4A being energized in the normal direction, lamp 50 GA of signal S4 is lighted, and relay 4B being energized in the reverse direction, lamp YB of this signal is also lighted. Signal S4 then indicates that the fourth section in advance is occupied by a train. Relays 5A and 5B are both 55 energized in the normal direction. It follows that both of the green lamps of signal S5 are lighted, so that this signal indicates that the four blocks in advance are unoccupied.

When a train moving toward the left enters 65 section 4—5, it will open track relay 5T, and the contacts 17 and 18 of this relay will then exclude relay 5B from its circuit and will close an auxiliary path for relay 4A, which path includes a resistance 24 to take the place of relay 70 5B. It follows that relay 4A will remain energized. Similarly, when the train advances into the section to the point at which track relay 5AT will open, contacts 16 and 19 of this relay will close another branch for the line circuit of 75

relays 4A and 5B, which branch includes a resistance 24, with the result that relay 4A will still remain energized. Of course, the opening of relay 5T will open the circuit for relay 5A, and the opening of relay 5AT will again open the circuit for relay 5A at another point.

In describing the structural details of the type of polarized relay I employ it was explained that auxiliary windings 20^a, 20^b, 23^a and 23^b were employed to make the neutral armature of such relays slow to pick up and slow to drop away unless disabled by the opening of contacts Q. These auxiliary windings are represented in the circuit drawings by a single loop designated with the numeral 23.

The A relays, as herein employed, have the loop 23 permanently closed and therefore the neutral contacts of these relays are at all times slow to pick up and slow to release. Because of this characteristic the front point of contact 11 of these relays always remains closed on the reversal of current flow through them and prevents the momentary closure of a circuit through the RA lamp at such time.

Similarly, owing to their slow pick-up characteristic, the contact 11 will remain in engagement with its back point during momentary energizations of the relay, which may occur under various conditions, and prevent the momentary interruption of the RA signal circuit and the momentary completion of the GA or YA signal circuit. Such an operation of the A relay may, for example, occur when a short train goes over a cut section.

The B relays, as herein employed, in addition to controlling signals, are employed as a pole-changing relay. It is desirable, when the circuit of a B relay is opened, that it drop its pole-changing contacts without delay so that, should a very short train clear the section immediately to the rear, the current supply through the A relay in the section immediately to the rear and the B relay in the second section to the rear will be immediately energized in the reverse direction to give a following train the proper restrictive indication without delay. If the pole-changing contacts of the B relay of the forward section are slow to drop, under the assumed circumstances, the current flow through the A and B relays of the rear sections will momentarily be in the normal direction before contacts 13 and 22 have had time to drop and will accordingly give a less restrictive indication before giving the desired more restrictive indication in response to their energization in the reverse direction. This possible objection is overcome by opening the auxiliary circuit of the B relay at contacts 109, corresponding to contacts Q of Fig. 3, of the track relay of the forward section at the same time that its main winding is opened by such track relay.

The circuits shown in Fig. 2 are very similar to those shown in Figs. 1^a and 1^b, the only difference being in the operation of the A and B relays in multiple instead of in series. The multiple arrangement has the advantage that necessity for use of external resistances such as 23 is avoided, and higher resistance line relays may be employed.

In the alternative scheme shown in Fig. 2, the circuits are applied to the track sections and signals shown in Fig. 1^b and the condition of the circuits are the same. This figure may accordingly be placed to the right of Fig. 1^a in substitution for Fig. 1^b. Each two adjoining sections

of Fig. 2 are provided with a line circuit which includes, in multiple, instead of in series, relay A for the forward section and relay B for the rear section. Current of normal or reverse polarity is supplied to such circuit according as the B relay for the section next in advance of the forward section is closed or open. Referring to sections 3-4 and 4-5, for example, the line circuit for these sections passes from the plus terminal of battery C3, through the front point of contact 13 of relay 3B, front point of contact 14 of track relay 4AT, winding of relay 3L, front point of contact 15 of relay 4T, winding of relay 4A, the front points of contacts 20 and 21 of track relays 4T and 4AT, respectively, and the front point of contact 22 of relay 3B to the minus terminal of battery C3. The relay 4A in picking up closes an operating circuit for relay 5B in multiple with that traced through 4A. The circuit of relay 5B extends from the left terminal of relay 4A, via the front point of contact 25 of relay 4A, the front points of contacts 16 and 17 of track relays 5AT and 5T, respectively, the winding of relay 5B, the front points of contacts 18 and 19 of track relays 5T and 5AT, respectively, to the right terminal of relay 4A. The relay 3B being closed, the current which is supplied to relays 4A and 5B is of normal polarity, so that relay 3L is energized when relays 4A and 5B are both energized in the normal direction. The polar contacts of the latter relays are therefore swung to the left. When relay 3B is open, and the circuits of relays 4A and 5B are otherwise prepared, current of reverse polarity is supplied first to relay 4A, and on its picking up, is extended to the relay 5B. Relays 4A and 5B will, accordingly, be energized in the reverse direction, so that their polar contacts will be swung to the right.

It will be apparent that the signal and train stopping device circuits of the modified arrangement are identical to those shown in Figs. 1^a and 1^b and that any further description of these circuits will therefore be unnecessary.

In the arrangement shown in Fig. 2, when a train moving toward the left enters section 4-5, it will open track relay 5T, and the contacts 17 and 18 of this relay will open the circuit of relay 5B which was heretofore closed through contacts 25 of relay 4A. When the train advances into the section to the point at which track relay 5T will open, the latter relay will likewise open the circuit of relay 5A, and the subsequent opening of relay 5AT will also open the circuit for relay 5A at another point.

The operation of the apparatus during the progress of the train through the succeeding sections shown in the drawings will be obvious from the foregoing without further explanation.

The train stopping devices D may, of course, be omitted, if desired, and the same thing is true of the approach lighting relays.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway track divided into sections, a first and a second polarized relay for each section, means including slow-acting pole-changing contacts on the first relay of each section operating according as such relay is energized or deenergized to supply current of normal

or reverse polarity to the second relay of the section next in the rear and to the first relay of the second section in the rear, track circuits for the sections including track relays for the control of 5 said polarized relays, and traffic governing means for the sections controlled by said polarized relays.

2. In combination, a railway track divided into sections, a first and a second polarized relay for each section, a line circuit for each two adjacent 10 sections including in series the second relay of the forward section and the first relay of the rear section, means including a set of slow-acting pole-changing contacts on the first relay of the section next in advance of such forward section for supplying each of said line circuits with current of normal or reverse polarity according as said last specified relay is energized or deenergized, track circuits for the sections including track relays for the control of said line circuits, and traffic governing means for the sections controlled by said polarized relays.

3. In combination, a railway track divided into sections, a first and a second polarized relay for each section, means including slow-acting pole-changing contacts on said first relay operating according as such relay is energized or deenergized to supply current of normal or reverse polarity to the second relay of the section next in the rear and to the first relay of the second section in the rear, track circuits for said sections including track relays for the control of said polarized relays, and traffic governing means for the sections controlled by said polarized relays.

4. In combination, a railway track divided into sections, a first and a second polarized relay for each section, a line circuit for each two adjacent sections including in series the second relay of the forward section and the first relay of the rear section, means for supplying each of said circuits with current of normal or reverse polarity according as the first relay of the section next in advance of such forward section is energized or deenergized, said means including slow-acting pole-changing contacts on said last specified relay, a track circuit for each section including a track relay having front contacts included in the two line circuits of the section, a shunt around the first relay of each section including a back contact of the track relay of such section, and signals for the sections controlled by said polarized relays.

5. In combination, a railway track divided into sections, a first and a second polarized relay for each section, a line circuit for each two adjacent sections including in series the second relay of the forward section and the first relay of the rear section, a source of current for supplying each of said circuits, means including slow-acting pole-changing contacts on the first relay of the section next in advance of such forward section for connecting said source to said circuit in one manner or another to actuate the relays in said circuit in a normal or reverse direction according as such first relay is energized or deenergized, 65 means operating when any one section is occupied by a train to open the line circuits including both the first and second relays of such section and to close a branch path for the circuit including the second relay of the section next in advance, and traffic governing means for the sections controlled by said polarized relays.

6. In combination, a railway track divided into sections, a first and a second polarized relay for each section, a line circuit for each two adjacent 70 sections including in series the second relay of

the forward section and the first relay of the rear section as well as an approach lighting relay for the section next in advance of such forward section, means including a set of slow-acting pole-changing contacts on the first relay of such section in advance of such forward section for supplying each of said circuits with current of normal or reverse polarity according as such relay is energized or deenergized, track circuits for the sections for the control of said line circuits, and 10 signals for said sections controlled by said polarized and approach lighting relays.

7. In combination, a railway track divided into sections, a first and a second polarized relay for each section, means including slow-acting pole-changing contacts on the first relay of each section according as such relay is energized or deenergized to supply current of normal or reverse polarity to the second relay of the section next in the rear and to the first relay of the second 20 section in the rear, track circuits for the sections including track relays for the control of said polarized relays, a train stopping device for such section, and a clearing circuit for each device closed if and only if both the first and second 25 relays of the associated section are energized in normal direction.

8. In combination, a railway track divided into sections, a first and a second polarized relay for each section, a line circuit for each two adjacent 30 sections including the second relay of the forward section with the first relay in multiple therewith through contacts of said second relay, means including the first relay of the section next in advance of such forward section for supplying each 35 of said line circuits with current of normal or reverse polarity according as said last specified relay is energized or deenergized, track circuits for the sections including track relays for the control of said line circuits, and traffic governing 40 means for the sections controlled by said polarized relays.

9. In combination, a railway track divided into sections, a first polarized relay for each section having slow acting neutral contacts in addition 45 to the usual polar contacts, a second polarized relay for each section also having slow acting neutral contacts in addition to the usual polar contacts, other neutral contacts on the second polarized relay for each section for supplying 50 current of normal or reverse polarity to the second polarized relay of the section next in the rear and to the first polarized relay of the second section in the rear, track circuits for said sections including track relays for the control of said 55 polarized relays, and traffic governing means for the sections having circuits including the neutral and polar contacts of one of said polarized relays as well as certain of the neutral and all of the polar contacts of the other of said polarized 60 relays.

10. In combination, a railway track divided into sections, a first and a second polarized relay for each section, means including slow-acting pole-changing contacts on the first relay of each section operated according as such relay is energized or deenergized to supply current of normal or reverse polarity to the second relay of the section next in the rear and to the first relay of the second section in the rear, another relay, track 70 circuits for the sections including track relays for the control of said polarized relays and said other relay, and traffic governing means for the sections controlled exclusively by said latter relays.

11. In combination, a railway track divided into sections, a first and a second polarized relay for each section, a line circuit for each two adjacent sections including in multiple the second relay of the forward section and the first relay of the rear section, means for supplying each of said relays with current of normal or reverse polarity according as the first relay of the section next

in advance of such forward section is energized or deenergized, track circuits for each section including a track relay having front contacts included in the circuit of the first relay of the associated section, and signals for the sections controlled by said polarized relays.
